UNITED STATES PATENT OFFICE.

FREDERICK ROBINSON, OF PHILADELPHIA, PENNSYLVANIA, ASSIGNOR TO
HENRY SCHADEWALD, OF SAME PLACE.

DESIGN FOR A BEDQUILT.

SPECIFICATION forming part of Design No. 25,291, dated March 24, 1896.

Application filed December 6, 1895. Serial No. 571,318. Term of patent 7 years.

To all whom it may concern:

Be it known that I, FREDERICK ROBINSON, a citizen of the United States, residing in Philadelphia, Pennsylvania, have invented a certain new and original Design for a Bed Spread or Quilt, of which the following is a specification.

My design for a bed spread or quilt is fully shown in the accompanying drawings.

Figure 1 illustrates the outlines of the complete design, and Fig. 2 represents one-quarter of the complete design with the details filled in.

The design comprises essentially a center piece A, an inner border B and an outer border D.

The design is a segregable one, each of the elements A, B and D in itself comprising a complete subdesign. The center A has a central rectangular figure a, and, surrounding the same, a design composed of conventional representations of leaves b and flowers d, the outer portion of the central figure being or-

namented with a block-weave design f. The inner border B comprises square figures g, h, i and m and oblong figures n, the figures g, h and i being ornamented with patterns of a geometrical character and the figures m and n containing representations of plants growing in pots or tubs. The outer border D consists of representations of strips or bands s interwoven after the manner of open-basket work, and in each of the squares inclosed by these bands is a block-weave ornament t.

I claim—

The design for a bed spread or quilt, substantially as described and as shown in the accompanying drawings.

In testimony whereof I have signed my name to this specification in the presence of two subscribing witnesses.

FREDERICK ROBINSON.
